UNITED STATES PATENT OFFICE.

GLENN H. CURTISS, OF GARDEN CITY, NEW YORK, ASSIGNOR TO CURTISS AEROPLANE AND MOTOR CORPORATION, A CORPORATION OF NEW YORK.

AIRPLANE LANDING-GEAR.

1,296,770.

Specification of Letters Patent.

Patented Mar. 11, 1919.

Original application filed December 22, 1916, Serial No. 138,499. Divided and this application filed April 5, 1918. Serial No. 226,860.

To all whom it may concern:

Be it known that I, GLENN HAMMOND CURTISS, a citizen of the United States, residing at Garden City, in the county of Nassau and State of New York, have invented 5 certain new and useful Improvements in Airplane Landing-Gears, of which the following is a specification.

My invention relates to airplanes and is a 10 division of application, Serial No. 138,499 filed December 22, 1916. More specifically the invention herein claimed relates to landing gear improvements which are fully set forth in the parent case. The term "landing gear" includes not only what is known 15 as the lading gear *per se* but the tail skid as well.

The fairing for the landing gear struts is 20 integrally united with the struts and with the longerons or other structural elements of the fuselage.

Its construction, size and form are such 25 that but a single pair of landing struts are required. These struts are preferably positioned in advance of the wing structure and beneath the motor mass. They thus support the weight of the motor. The fairing, which is carried back from the struts is attached to the longerons in the vertical plane 30 of the wing structure. Its function is to not only streamline the struts of the landing gear but to increase their strength and widen them at their points of attachment with the fuselage. Head resistance or drag is 35 thus appreciably reduced.

The tail skid of the landing gear is characterized by an improved arrangement of tail skid parts in which the cushioning means is disposed directly above the point of 40 contact and inclosed completely within the fuselage. This disposition of the tail skid parts is better and more effective in that the cushioning means takes up the direct impact of ground operation and carries it directly into the fuselage. Moreover, a minimum number of parts are exposed to the air 45 rush incident to flight.

Of the drawings, wherein like characters 50 of reference designate like or corresponding parts:—

Figure 1 is a front end elevation of an airplane having the improved features of the landing gear embodied in it;

Fig. 2 is a side elevation of the forward end of the fuselage with portions of the 55 wing structure, etc., removed;

Fig. 3 is a detail view partly in section and partly in elevation of the empennage;

Fig. 4 is a view similar to Fig. 2 showing the construction and arrangement of parts 60 at the tail end of the fuselage, and

Fig. 5 is a detail view, in section, of the tail skid.

In the embodiment of the invention selected for illustration the supporting surfaces 65 are designated as 10 and 11. They extend intermediately across the fuselage 12 in superposed relation and are interconnected by wing posts 13, which diverge outwardly from the lower supporting surface 11 to the 70 upper supporting surface 10. These wing posts are carried beyond the lower supporting surface 11 and inclined forwardly and downwardly for connection at their lower ends with the landing gear axle 14. They 75 thus constitute landing struts although related to the landing gear in a manner somewhat different from the usual relation of the landing gear struts.

The wheels 15 of the landing gear are 80 mounted between the strut ends (referring to the struts formed by the continuation of the wing post 13 beyond the lower surface) and are inwardly braced or connected with the fuselage by landing gear struts 16. 85 These struts 16 are preferably constructed of metal and integrally united with the lower longerons 17 of the fuselage at points directly beneath the engine bed 18 so that the weight of the motor mass will lie directly 90 above the landing gear axle. Said struts 16 constitute the total number of what may be properly designated landing gear struts although the extended portions of the wing posts 13 function in a related capacity. As 95 a further means of increasing the strength of the landing gear without increasing its head resistance fairing 19 for the struts 16 is provided. It is likewise constructed of metal and integrally united with the struts 100 16 and with the longerons 17. From the lower ends of the struts it increases in depth so that at its point of connection with the longerons it is of maximum depth. This construction of the fairing is desirable in 105 that it distributes the landing and ground

running impacts over a wider area of the fuselage. When considered in connection with the wing post extensions the fairing 19 constitutes a system of bracing of ample strength. Fairing 20 is used to streamline the axle which is devoid of shock absorbing means. It is the arrangement, construction and shape of fairing 19 however which gives to the landing gear its required strength.

10 Through the above arrangement of landing gear struts it is possible to eliminate and entirely dispense with the usual forwardly and downwardly inclined landing struts. Although the wing post extensions carry a portion of the landing stresses into the fuselage by way of the wing structure the fairing 19 takes up the major portion of the landing stresses. In other words the wing post extensions act as auxiliary landing struts and 20 function primarily as elements of the wing structure truss.

The tail skid, which is located at the rear end of the fuselage, is designated as an entirety by the numeral 21. It comprises a 25 tension rod 22, a guide rod 23 and ground contact member 24. The ground contact member 24 is constructed in the form of a spoon with its convex surface lowermost. It is placed directly beneath a spring 25 30 closed in the stern post 26 of the fuselage. The guide 23 is pivotally connected as at 27 with the spoon 24 and rigidly connected as at 28 with the spring 25. The spring 25 at its inner upper end is rigidly fastened as at 29 to 35 and within the stern post to yieldingly resist vertical displacement of the spoon. The rod 22 at its forward end is pivotally connected as at 30 with one of the horizontally extending fuselage struts and rigidly connected by brazing with the spoon 24 at its 40 rear end. It provides a tie means for preventing rearward displacement of the spoon when coming in contact with the ground while the airplane is in motion. A shoe 31 45 may be provided to take up the wear on the tail skid if desired.

A tail skid thus constructed is especially effective in that the landing and ground running impacts occur at a point directly beneath its cushioning means. The connection at 27 is made sufficiently loose to prevent binding of the spoon 24 when vertically displaced. By inclosing the cushioning means or spring 25 within the stern post 26 50 of the fuselage it (the spring) is completely hidden and removed from view so as to offer no resistance whatsoever while the machine is in flight. Furthermore, the location of the spring in the manner indicated is better and stronger than at a point longitudinally removed from the transverse vertical plane of the point of contact.

While I have described my invention in detail in its present preferred embodiment, 60 it will be obvious to those skilled in the art

after understanding my invention, that various changes and modifications may be made therein without departing from the spirit or scope thereof. I aim in the appended claims to cover all such modifications and changes.

What is claimed is:—

1. In a landing gear for airplanes, the combination with the fuselage, of downwardly extending struts connecting with the fuselage at their upper ends, and fairing for the struts of gradually increasing depth from the lower strut ends upwardly, the fairing being connected with the fuselage to conjointly function as strut braces. 80

2. In a landing gear for airplanes, the combination with the fuselage, of downwardly divergent struts connecting with the fuselage at their upper ends, and fairing for the struts of gradually increasing depth from their lower ends upwardly, the arrangement of the fairing being such that the struts are braced rearwardly and the landing impacts accordingly directed over a wider area of the fuselage. 90

3. In a landing gear for airplanes, the combination with the fuselage, of a pair of downwardly divergent struts connecting with the fuselage at their upper ends, and fairing for the struts of gradually increasing depth from the lower strut ends upwardly, the fairing comprising separate webs extending back from the struts and connected directly with the fuselage to conjointly function as strut braces. 95

4. In a landing gear for airplanes, the combination with the fuselage, the fuselage including longerons as structural elements thereof, of a pair of downwardly extending struts connecting with the fuselage at their upper ends, and fairing for the struts of gradually increasing depth from the lower strut ends upwardly, said fairing comprising separate webs extending back from the struts and directly connecting with the fuselage to 105 conjointly function as strut braces. 100

5. In a landing gear for airplanes, the combination with the fuselage, of a pair of downwardly divergent struts connecting with the fuselage at their upper ends and constituting the only struts of the landing gear connecting with the fuselage, and fairing for the struts of gradually increasing depth from the lower strut ends upwardly, 115 said fairing comprising separate webs extending back from the struts and directly connecting with both the struts and the fuselage to brace the former and accordingly distribute the landing impacts over a 120 wider area of the fuselage. 125

6. In a landing gear for airplanes, the combination with the fuselage and supporting surfaces, of a pair of downwardly divergent struts connecting with the fuselage 130

at their upper ends, said struts being the only landing gear struts connecting with the fuselage, and a pair of downwardly convergent struts connecting at their upper 5 ends with the supporting surfaces, said last mentioned struts, when viewed from the side, being inclined rearwardly and up-

wardly from the lower strut ends and constituting the only landing gear struts connecting with the supporting surfaces. 10

In testimony whereof I hereunto affix my signature.

GLENN H. CURTISS.
